(57) **CLAIM**

The ornamental design for an upper portion of a front face
segment of a refrigerator door, as shown and described.

DESCRIPTION

FIG. 1 is a front perspective view of an upper portion of a
front face segment of a refrigerator door showing our new
design.

FIG. 2 is an enlarged front perspective view thereof.

FIG. 3 is a front view thereof.

FIG. 4 is a left side view thereof.

FIG. 5 is a right side view thereof.

FIG. 6 is a top view thereof.

FIG. 7 is a cross-sectional view taken along the line 7—7 of
FIG. 3; and,

FIG. 8 is a cross-sectional view taken along the line 8—8 of
FIG. 3.

It will be understood that the bottom view is not visible
during normal use. It will be further understood that the
hidden line showing throughout the drawings of various
portions of the remainder of the refrigerator is for illustrative
purposes only and forms no part of the subject invention.
